UNITED STATES PATENT OFFICE.

JOHN S. CAMERON, OF ELLIOTT, ILLINOIS.

GRAIN DOOR.

Application filed January 6, 1925. Serial No. 362.

To all whom it may concern:

Be it known that I, JOHN S. CAMERON, a citizen of the United States, residing at Elliott, in the county of Ford and State of Illinois, have invented a new and useful 5 Grain Door, of which the following is a specification.

The present invention relates to grain car doors and aims to provide a novel form of 10 door which may be readily and easily swung to a position exteriorly of the car and supported in such position to permit the car to be used for carrying material other than grain.

15 Another object of the invention is to provide a door of this character including a plurality of hinged sections which may be moved to their active or inactive positions at the will of the operator to facilitate the 20 loading and unloading of the car.

A still further object of the invention is 25 to provide means for adjusting the door vertically to eliminate any possibility of the door dragging on the floor of the car while it is being transferred from a position interiorly of the car to the exterior thereof, or vice versa.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed, without departing from the spirit of the invention.

Referring to the drawings:

40 Figure 1 is a side elevational view illustrating a grain car door constructed in accordance with the invention as closing the door opening of the car.

45 Figure 2 is a sectional view taken on line 2-2 of Figure 1.

Figure 3 is a sectional view taken on line 3-3 of Figure 1.

Figure 4 is a sectional view taken on line 4-4 of Figure 1.

50 Figure 5 is a sectional view taken on line 5-5 of Figure 1.

Figure 6 is a sectional view taken on line 6-6 of Figure 1.

55 Referring to the drawings in detail, the reference character 5 indicates a car which

is provided with the usual opening 6 normally closed by means of the sliding closure 7 provided with brackets 8 which support suitable rollers that move along the track 9. Suitable cleats indicated at 10 are provided for holding the sliding closure 7 to its proper position.

The grain door which forms the essence of the invention is indicated generally by the reference character 10, and includes a 65 plurality of hinged sections 11, which sections are supplied with locking members 12 that are adapted to swing within suitable keepers to lock the sections 11 in their active positions.

The lowermost section of the grain door is supplied with an opening that is normally closed by the hinged closure 13, sliding bolts 14 being provided and adapted to engage within keepers positioned in the floor 75 of the car to hold the hinged closure 13 in its closed position.

Secured to the grain car door are supporting chains 15 that carry brackets 16 at their upper ends, which brackets have rollers 17 80 that move within the tubular track section 18, the tubular track section 18 being formed with a longitudinal slot to allow the rollers to fit within the track section.

This tubular track section 18 is pivotally 85 supported at 19, one end thereof being positioned within the slot 20 of the support 21 so that when the weight of the grain door exerts a pressure on the outer or free end of the track section 18, the rear end of the 90 track section 18 will be held against movement by its contact with the walls of the slot of the securing member.

In order that the tubular track section 18 will be held in a position to permit the grain door to be transferred from the track section 18, a latch member 22 is provided and disposed adjacent to the outer end of the slot 20 so that as the track section 18 is 95 swung on its pivot, the track section will fall behind the latch member 22 to hold the track section against movement.

Mounted exteriorly of the car is a track section 24 which is formed with a beveled end 25 adapted to be engaged by the beveled end 26 of the track section 18 so that when the track section 18 is moved to a position as indicated in dotted lines in Figure 6 of the drawings, the beveled ends 25 and 26 will 105 contact to provide a continuous track sec- 110

tion and permit the grain door to be moved onto the track section 24 and to a position exteriorly of the car.

In order that the chains 15 may act to hold the sections 11 of the grain car door in a vertical position, hasps 27 are carried by one of the sections 11 and are adapted to pass over the keepers 28, which keepers accommodate the hook members 29 for securing the hasps against movement. These hasps 27 are provided with offset portions providing clearances for the chains.

From the foregoing it will be obvious that due to this construction, the grain car door 15 may be readily and easily moved to its active position, or moved out of its active position, adapting the car for use in transporting various types of articles.

I claim:

20 1. In a freight car door, a body portion, a door opening, a stationary track section mounted exteriorly of the door opening, a track section pivotally mounted within the body portion and adapted to move into engagement with the first mentioned track section to form a continuation thereof, a support extending inwardly from the wall of the car and having a slot, one end of the

pivoted track section adapted to move in the slot, a spring member disposed adjacent to the slot and adapted to engage the pivoted track section to lock the pivoted track section against movement, and a movable door section supported on the pivoted track section.

2. In a freight car door, a body portion having a door opening, a stationary track section supported exteriorly of the body portion, a track section pivotally mounted within the body portion, a support extending inwardly and arranged near the door opening, said support having a slot, one end of the track section adapted to move in the slot, means disposed adjacent to one end of the support and adapted to engage the pivoted track section to hold the pivoted track section against movement, and a sliding door carried by the track section.

In testimony that I claim the foregoing as my own, I have hereto affixed my signature in the presence of two witnesses.

JOHN S. CAMERON.
